SANITARY BRUSH

Frank Satz and Mel Berns, Los Angeles, Calif.

Application August 5, 1938, Serial No. 223,154

7 Claims. (Cl. 15—185)

This invention relates generally to brushes and more particularly to holders therefor by which the brush bristles can be protected against contamination during such periods as the brush is not in use.

- An object of the invention is to provide a brush particularly adapted, although not necessarily for use in the art of "make up" as practiced by theatre and cinema artists, and structurally characterized by extremely simple and highly efficient means which is manually operable by a positive mechanical operation to expose the brush bristles for use or conceal the bristles in a practically sealed housing when not in use, so as to adequately protect the bristles from such contacts or exposure as might contaminate the bristles, all to the end of promoting sanitation and precluding premature discarding of the brush because of an unclean condition thereof.
- Another object of the invention is to provide a sanitary brush wherein the brush bristles are adapted to be enclosed in housing sections which are rockably mounted on the handle of the brush for positive actuation to expose or conceal the bristles by a cam common to the housing sections, and manually actuatable in an axial direction relative to the handle through the medium of a plunger in the handle, to which the cam is fixed.
- A further object of the invention is to provide a sanitary brush of the above described character wherein the various parts thereof can be easily and quickly assembled to form the complete brush without the use of extraneous fastening means, and in a manner for the parts to be self-maintained in proper working relationship.

With these and other objects in view, the invention resides in the combinations, arrangements and functional relationships of elements as set forth in the following specification and particularly pointed out in the appended claims.

In the accompanying drawing:

Figure 1 is a view of the brush in side elevation;

Figure 2 is a longitudinal sectional view taken on the line 2—2 of Figure 1, and showing the brush bristles enclosed by the housing;

Figure 3 is a view similar to Figure 2, and illustrating the bristles exposed for use;

Figures 4 and 5 are enlarged transverse sectional views taken on the lines 4—4 and 5—5 of Figure 2;

Figure 6 is a fragmentary longitudinal sectional view of the head portion of the brush handle;

Figure 7 is a perspective view of one of a plurality of identical housing sections which are co-actable to form the bristle enclosing housing;

Figure 8 is a fragmentary view in side elevation, of a second form of sanitary brush embodying this invention;

Figure 9 is a view in side elevation of the second form of sanitary brush, at a right angle to Figure 8.

Referring specifically to the drawing, and particularly to Figures 1 to 7, inclusive, this form of the invention comprises a handle 10 composed of a tubular shank 11 of uniform diameter having an enlarged cylindrical portion or head 12 at one end, the bore 13 of which head is co-axially related to, and somewhat larger in diameter than the bore 14 of the shank 11.

At diametrically opposed points, the head 12 is provided with openings 15 preferably of generally rectangular outline and extending through the annular wall 16 thereof. The internal surface of the wall 16 is provided with longitudinally extending grooves 17 extending from the openings 15 to the free end of the head.

A brushing element 18 having bristles 19 is fixed to one end of an actuating rod 20 slideably freely in the bore 14 of the shank 11 and having a force fit at its other end in the base 21 of a cup shaped cap 22, the bore 23 of which telescopically receives the adjacent end of the shank.

Adjacent the brushing element 18 and fixed to the rod 20 so as to work in the bore 13 of the head 12, is an actuator in the form of a cam 24 for the two identical sections 25 of a streamlined housing 26 which is adapted to enclose or expose the brushing element 18 according as the latter occupies the retracted position shown in Figure 2 or the advanced position shown in Figure 3.

Each housing section 25 is provided with a longitudinal extension 27 terminating in a pivot lug 28 or trunnion 28 which is generally rectangular in outline to freely fit in one of the openings 15, whereas the extension 27 is freely received in one of the grooves 17, all to the end of rockably mounting the housing section on the handle.

It will be noted that shoulders 29 and 30 on each housing section confine the latter against displacement axially of the handle, and that the cam 24 is of a generally semi-spherical shape to ride against the internal cam surfaces 31 of the housing sections for co-action with such surfaces in positively rocking the sections to their closed or opened positions according as the cam is actuated to occupy the advanced or retracted position shown, respectively, in Figures 2 and 3.

In the closed position of the housing sections, the cam 24 tightly engages the cam surfaces 31 at a point substantially opposite the lugs 28, and exerts sufficient pressure against the surfaces to maintain the confronting flat faces 32 of the sections in sealing contact with each other so as to adequately protect the brushing element from contamination.

In the operation of the invention, the brushing element 18 is exposed for use by pushing against the cap 22 so as to cause the cam 24 to ride upon the surfaces 31 and positively spread the tip ends of the housing sections 25 only sufficiently for the brushing element to pass freely therebetween. Upon reversely moving the cap 22 relative to the handle 10, the reverse movement of the housing sections will be effected until the brushing element is fully retracted and sealed in the housing, this position of the element being definitely limited by co-action of a shoulder 32 on the rod 20 with a shoulder 33 in the head 12.

To assemble the various parts of the device, the two housing sections 25 are applied to the handle 10 as shown in Figure 3, following which the rod 20 is inserted between the sections into the handle 10 and then forced into the cap 22. The cam 24 now positively prevents displacement of the lugs 28 from the openings 15, so that the parts will be maintained assembled in their proper working relationship.

Reference will now be had to Figures 8 and 9, wherein is disclosed a second form of rockable mounting for the housing sections 25a in the head 12a of the handle 10a. The head 12a is provided with obliquely disposed slots 34 at diametrically opposed points and extending from the periphery of the head to terminate in laterally offset bearings 35 for trunnions 36 on extensions 37 of the housing sections, which extensions work in slots 38 of the head 12a. When the housing sections are applied to the head, and the rod 20 is assembled therewith, the cam 24 will co-act with the sections in the manner previously described, to positively prevent displacement of the trunnions 35 from the bearings so as to rockably mount the sections on the head to function in a manner identical to that described for the heads 25.

What is claimed is:

1. A device of the class described comprising a handle; a housing at one end of the handle and composed of a plurality of sections; co-acting means on the handle and housing sections by which the latter are pivotally mounted to occupy an open position wherein the sections are spread apart sufficiently for the passage of a brush, and a closed position wherein the sections are adapted to co-act in sealing the brush within the housing; said means including trunnions on the sections and bearing portions on the handle opening in a direction laterally of the length thereof to require that the housing sections be moved laterally with respect to the handle in order to be applied to and removed from the handle; means reciprocably mounting a brush in the handle to occupy a retracted position between said sections, and an advanced position beyond the end of the housing; and means on said mounting means co-actable with the housing sections to move them to closed or open position according as the brush is moved to retracted or advanced position and to prevent lateral displacement of the sections from their pivotal mountings.

2. A device of the class described comprising a handle; a housing at one end of the handle and

composed of a plurality of sections rockably mounted to occupy an open position wherein the sections are spread apart sufficiently for the passage of a brush, and a closed position wherein the sections are adapted to co-act in sealing the brush within the housing; an actuating rod reciprocably mounted in the handle and adapted to support a brush for movement thereby to occupy a retracted position between the housing sections, and an advanced position exteriorly of the housing; the housing sections having internal cam surfaces; and a cam on said rod in wiping contact with the cam surfaces of said sections to move them to closed or open position according as the rod is retracted or advanced.

3. A device of the class described comprising a handle composed of a tubular open ended shank having a hollow head at one end; a housing composed of a plurality of pivoted sections rockably mounted in said head to occupy open and closed positions; an actuating rod reciprocably mounted in said shank and adapted to support a brush at one end thereof for movement therewith to occupy a retracted position between the housing sections, and an advanced position exposed from the housing; a cam on said rod co-actable with internal surfaces on each side of said pivots of the housing sections to move them to closed or open position according as the rod is retracted or advanced; and a cup shaped actuating cap fixed to the other end of said rod and telescopically associated with said shank of the handle.

4. A device of the class described comprising a handle composed of a tubular open-ended shank having a hollow head at one end; a housing composed of a plurality of sections having trunnions mounted in said head to support the sections for rocking movement laterally of the handle to occupy open and closed positions; an actuating rod reciprocably mounted in said shank and adapted to support a brush for movement therewith to occupy a retracted position between said sections, and an advanced position exposed from the housing; a cam on said rod interposed between said sections; means defining cam surfaces on the confronting sides of said sections with which said cam co-acts to move the sections to closed or open position according as the actuating rod is retracted or advanced; and an actuating cap fixed to the other end of said rod and telescopically associated with said shank of the handle.

5. A device of the class described comprising a handle composed of a tubular open ended shank having a hollow head at one end; a housing composed of a plurality of sections; said sections having extensions provided with lugs defining trunnions; said head having recesses freely receiving said extensions, and openings freely receiving said lugs to rockably mount the sections to occupy open and closed positions; an actuating rod reciprocably mounted in said shank and adapted to support a brush for movement therewith to occupy advanced and retracted positions; a cam on said rod, interposed between said sections and co-actable therewith to confine them against displacement from their mountings and to move them to open or closed position according as the rod is advanced or retracted; and an actuating cap fixed to the rod and telescopically associated with said shank.

6. A device of the class described comprising a handle; a housing carried by the handle at one end thereof and composed of a plurality of sections pivotally mounted to occupy open and closed positions; means mounting a brush in the

handle for movement to occupy a retracted position between said housing sections, and an advanced position wherein the brush is exposed from the housing; cam surfaces on the housing sections; and a cam on said mounting means interposed between said sections, for co-action therewith in preventing displacement of the sections from their pivotal mountings, and to coact with said cam surfaces in moving the sections to closed or open position according as the brush is moved to retracted or advanced position.

7. A device of the class described comprising a handle; a housing at one end of the handle and composed of a plurality of sections; the handle having slots extending obliquely from the outer

surface of the handle at opposite sides thereof and provided with laterally offset bearings; the housing sections having trunnions entering said slots and seating in said bearings to pivotally mount the housing sections to occupy open and closed positions; means adapted to reciprocably mount a brush in the handle to occupy retracted and advanced positions; and means on said mounting means co-actable with the housing sections to open or close them according as the brush is retracted or advanced, and to prevent displacement of the trunnions from said bearings.
